UNITED STATES PATENT OFFICE.

ARTHUR D. GILBERT, OF DUNSEITH, NORTH DAKOTA.

PIPE.

1,276,751.

Specification of Letters Patent. Patented Aug. 27, 1918.

Application filed May 6, 1918. Serial No. 232,815.

To all whom it may concern:

Be it known that I, ARTHUR D. GILBERT, a citizen of the United States, and a resident of Dunseith, in the county of Rolette 5 and State of North Dakota, have invented certain new and useful Improvements in Pipes, of which the following is a specification.

My invention is an improvement in pipes, 10 and has for its object to provide a device of the character specified wherein a smoke chamber or bore is provided at one side of the tobacco chamber with which the said tobacco chamber communicates by a series 15 of openings spaced apart vertically from each other, and wherein means is provided in connection with each opening for plugging the same, operable outside the pipe, the smoke bore or chamber having also re- 20 movable ends to facilitate cleaning of the same.

In the drawings:

Figure 1 is a perspective view of the improved pipe;

Fig. 2 is a partial longitudinal section;

Fig. 3 is a view similar to Fig. 2, showing a modified construction.

In the present embodiment of the invention, the improved pipe, which may be of 30 any desired material, as, for instance, wood, comprises a bowl or tobacco chamber 1, a stem portion 2 and a bit 3. At the front of the tobacco chamber is provided a smoke chamber 4 which extends vertically from 35 the top of the tobacco chamber below the bottom thereof, communicating with the bore of the stem portion 2.

The smoke chamber 4 is open at both ends, the upper end being closed by a pivot- 40 ed cover 5 and the lower end by a removable plug 6. By swinging the cover aside and removing the plug access is permitted to the full extent of the smoke chamber.

The tobacco chamber communicates with 45 the smoke chamber by a series of openings, three in the present instance, the said openings being indicated at 7, 8 and 9, respectively, the openings being spaced apart in a vertical row. The outer wall of the smoke 50 chamber has an opening 10 in alignment with each of the openings 7, 8 and 9, and in each of these openings 10 is mounted a plunger 11, each plunger having a head at 55 its outer end, for convenience in manipulat- 60 ing the same. The plungers at their inner 65 ends are of a size to fit the openings 7, 8 and 9 and to close the same when they are shoved inwardly, as indicated at the top of Fig. 2.

In use, the pipe is filled in the usual manner, the tobacco being placed in the tobacco chamber, and all of the plungers 2 withdrawn as indicated in Fig. 1. The tobacco is now lighted in the usual manner and when it is burned below the opening 9 the plunger 11 thereof is moved into closed position indicated at the top of Fig. 2. The smoke now passes through the opening 8 until the tobacco burns below the said opening, when this opening 8 is closed and the smoke passes 70 through the opening 7. The pushing in of the plunger also cleans the openings 7, 8 and 9.

With the improved pipe the moisture from the burning tobacco will not pass through the whole of the load, thus making the tobacco soggy and strong in an increasing amount as it burns down, but will only pass through that depth of the tobacco between two smoke openings. This construction of 80 pipe eliminates the unpleasant bubbling of the moisture condensed in the stem and prevents clogging of the same. The tar condensed in the smoke passages may be easily cleaned, by means of a swab passed entirely 85 through the smoke chamber.

In the embodiment of the invention shown in Fig. 3, the bowl 12 has two smoke chambers 13, one at the front and one at the rear of the bowl, that is, one at the bit and one 90 at the opposite side of the bowl from the bit. Two openings 14 lead from each smoke chamber to the bowl, and plungers 15 are mounted to slide in openings 16 in the outer walls of the smoke chambers, the said openings 16 95 alining with the openings 14. The smoke chambers communicate with the bore of the stem portion 17 of the pipe, and there is an opening at the bottom of that smoke chamber remote from the bit, which is normally closed by a plug 18. The operation is the same as in the construction of Figs. 1 and 2, but there will be a freer draft because of the oppositely arranged openings 14. The tops of the smoke chambers are 100 covered by plates 19 in the same manner as the top of the smoke chamber 4 is covered.

I claim:

1. A pipe comprising a bowl consisting of a tobacco chamber, a smoke chamber and 110

2
a stem, a bit connected with the stem, said smoke chamber extending up alongside the tobacco chamber and communicating with the bore of the stem portion at the bottom 5 of the smoke chamber and with the tobacco chamber by a series of openings spaced apart vertically from each other, a plunger slidable in the outer wall of the smoke chamber at each opening and designed to 10 engage and close and clean the same when pushed inwardly, and removable closures at the ends of the smoke chamber.

2. A pipe comprising a bowl consisting of a tobacco chamber, a smoke chamber and 15 stem, a bit connected with the stem, said smoke chamber extending up alongside the tobacco chamber and communicating with the bore of the stem portion at the bottom of the smoke chamber and with the tobacco 20 chamber by a series of openings spaced apart vertically from each other, and a plunger slidable in the outer wall of the smoke chamber at each opening and designed to

engage and close and clean the same when pushed inwardly.

3. A pipe comprising a bowl consisting of a tobacco chamber, smoke chambers and a stem portion, said smoke chambers extending up alongside the tobacco chamber and communicating with the bore of the stem portion at the bottom of the smoke chamber and with the tobacco chamber by a series of 30 openings spaced apart vertically from each other, and a plunger slidable in the outer walls of the smoke chambers at each opening and designed to engage and close the same when pushed inwardly.

4. A pipe comprising a bowl having a smoke chamber extending upwardly alongside thereof and having spaced openings 40 opening into the smoke chamber, said smoke chamber communicating with the stem portion, and a plunger for closing and cleaning each of the said openings.

ARTHUR D. GILBERT.
